CLAIM

The ornamental design for a water closet, as shown and described.

DESCRIPTION

FIG. 1 is a front view of a water closet embodying our design;

FIG. 2 is a top view thereof;

FIG. 3 is a left side view thereof, the right side being a mirror image of the left side; and,

FIG. 4 is a perspective view thereof.

The dotted lines shown in FIG. 4 are for purposes of showing environment only and form no part of the claimed design.
